UNITED STATES PATENT OFFICE.

FRANCIS W. BORKES, OF CLEVELAND, OHIO, ASSIGNOR, BY MESNE ASSIGNMENTS, TO MOTOR TERMINALS COMPANY, OF NEW YORK, N. Y., A CORPORATION OF DELAWARE.

HOIST.

Application filed January 27, 1922. Serial No. 532,152.

This invention relates to hoists designed for use in the freight handling systems especially adapted for use in freight stations and its principal object is to facilitate the transfer of freight from one freight station to another. These systems ordinarily have a series of trucks with removable box bodies, said bodies being taken off the truck by a hoist and deposited by the hoist in the desired position in the freight house where it is loaded and then placed upon the truck by the hoist. For the efficient operation of such systems it is necessary for all freight stations in the city to be equipped with the system. Then a truck will bring a load of freight from one freight station to the other where it is taken off the truck and another loaded body is placed thereon to be returned to the first freight station. In this way the trucks do not have to wait for the loading and unloading, and also the body can be taken to the freight itself instead of wheeling and carrying the freight to the body.

This system has been installed in various places and is proving very satisfactory.

As stated above, this invention is an improved hoist or crane for removing from or placing on said trucks the bodies or boxes in which the freight is loaded. In order to do this satisfactorily the hoist must be so designed that it will not only lift the bodies and carry them from place to place, but it also must be so designed that the body can be rotated through a few degrees so that it can be placed in the correct position upon the truck without any trouble. As will be readily seen, if the hoist or crane were not capable of giving the body a slight rotation the truck upon which it is to be deposited would have to be parked directly under the hoist and exactly parallel to the sides of the body carried by the hoist. However, if the hoist can rotate the body a few degrees no particular care need be taken in positioning the truck under the body to be removed.

In the drawings Fig. 1 is a top plan view of the apparatus; Figs. 2, 3 and 4 are sections on the lines 2-2, 3-3 and 4-4 respectively, of Fig. 1, and Fig. 5 is a section on the line 5-5 of Fig. 2.

Two spaced rails 1 and 2 upon which the hoist or crane rides (which rails may be built up the channel irons and plates as shown or may be ordinary I-beam) are suspended

from the ceiling of the building. The hoist or crane comprises two pairs of channel irons 3 and 4 and 5 and 6, the channel irons 3 and 4 being placed on opposite sides of the rail 1 and connected across the bottom by cross pieces 7, and the channels 5 and 6 being placed on opposite sides of the rail 2 and connected across the bottom by cross pieces 8. The channel irons 4 and 5 are connected together by cross beams 9, 10, 11 and 12.

The channel irons 3, 4, 5 and 6 have attached thereto studs 13 and 14, the studs 13 having rotatably mounted thereon track wheels 15, which ride on the flanges of the rails 1 and 2, and roller or ball bearings 16 between the rear faces of the track wheels 15 and the channel irons 3, 4, 5 and 6. The studs 14 have rotatably mounted thereon track wheels 17 to which are rigidly attached gears 18. Roller bearings 19 similar to the bearings 16 are placed between the gears 18 and the channel irons 3, 4, 5 and 6.

A shaft 20, carried in bearings 21 attached to the lower flanges of the channel irons 3, 4, 5 and 6, has gears 22 thereon which mesh with the gears 18. One end of the shaft 20 has mounted thereon a wheel 23 which carries an endless chain or cable 24 by which the shaft 20 is rotated by a person on the floor. It is to be understood that if so desired the wheel 23 and cable or chain 24 may be placed on either or both ends of the shaft 20 as desired; also the shaft 20 may be rotated by a motor carried by the frame, if it is desired to do so. By rotating the shaft 20 the gears 22 and 18 and consequently the track wheels 17 are rotated which will cause the frame carried by the wheels 15 and 17 to be moved along the tracks 1 and 2, the direction of the movement depending upon the direction of rotation of the shaft 20.

A shaft 25 is carried in brackets 26 depending from the lower flanges of the channels 3, 4, 5 and 6 midway between the studs 13 and 14. Drums 27 are secured to the shaft 25 near the ends thereof beneath the rails 1 and 2. The shaft 25 is rotated by a motor 28 (carried on cross beams 29 extending between the beams 11 and 12) through gears 30 and 31 and a worm gear reduction carried in a housing 32 suspended from the cross bars 10 and 11. 33 indicates shaft couplings.

Four frames, generally denoted by 34

which consist of horizontal top members 35, vertical end members 36 and intermediate members 37, parallel to the end members 36 and lower horizontal connecting members 38 which connect the lower ends of the members 36 and 37, are slidably mounted upon the roller bearings 16 and 19 between the wheels 15 and 17 and the channels 3, 4, 5 and 6. As is clearly shown in the drawings, the lower members 38 of the frames 34 are connected by shafts 39 and 40, the shafts 39 carrying sheaves 41 and the shafts 40 carrying sheaves 42. As will be seen by the drawings the sheaves 41 are in alignment with each other, and the sheaves 42 are in alignment with each other. Depending from the cross pieces 7 and 8 are eyes 43 to which one end of cables 44 is secured, the other ends of said cables being secured to the drum 27 and wound thereon in opposite directions as is shown clearly in Fig. 3. The cables 44 run from the drum 27 and over the sheaves 42, thence downwardly and around the sheave wheels 45 which carry sheave blocks 46 and thence upwardly and over the sheaves 41 and thence to the eyes 43 where they are secured. This is clearly shown in Figs. 2 and 3.

A shaft 47 is carried directly beneath the studs 13 by brackets 48 which project downwardly from the lower flanges of the channels 4 and 5 and has gears 49 and 49^a thereon which mesh with racks 50 and 50^a which are carried by the downwardly projecting members 36 and 37 on one end of the two frames 34 mounted between the tracks 1 and 2. As will be noted in Fig. 2, the rack 50 is below the gear 49 while the rack 50^a is above the gear 49^a. The shaft 47 is rotated by a wheel 51 and endless chain or cable 52, said wheel and chain being similar to the wheel and chain 23 and 24 respectively. When the shaft 47 is rotated, the opposing pairs of frames 34 will be caused to move in opposite directions by the gears 49 and 49^a and racks 50 and 50^a. The frames 34 will move easily, due to the fact that they are mounted on the roller bearings 16 and 19. The shifting of the frames 34 will not affect the height of the sheave blocks 46 as the distances between the fixed ends of the cables are always constant no matter what positions the frames are in.

In operation the device is used as follows: The hoist or crane is brought over the box or body to be moved, (said body being indicated in dot and dash lines in Figs. 2 and 3) by rotating the shaft 20, gears 22 and 18 and consequently the track wheels 17. When it is brought over the body, the shaft 25 and consequently the drums 27 are rotated by the motor 28 and interposed gearing which allows the four sheave blocks 46 to be lowered until they are fastened to hooks carried by the body or box. Then the shaft 25 is ro-

tated in the opposite direction which raises it from the truck or floor as the case may be and it is carried to the place desired. When lowering the box, if any angular movement is desired, this is secured by rotating the shaft 47 which will move the frames 34 and consequently the sheave blocks 46 in opposite directions which will give a slight angular movement to the box or body carried by the blocks 46.

It will be seen that by the means described I have provided for shifting the hoisting cables longitudinally with respect to the main track of the crane, the cables at opposite sides being shifted in opposite directions, so that a box or load suspended by the cables will be "skewed" more or less with respect to the line of travel of the crane and will thereby be disposed in an angular position so that it may be lowered in proper position on a truck, even if the latter is not located in a position exactly parallel to the travel of the crane. This result is particularly desirable in installations of this kind where the load is suspended at four points. A load suspended from a single point can of course be quite readily turned by hand, but this would be attended with some difficulty in a crane of the present type. By the invention disclosed this turning or skewing can be accomplished by manipulation of the rope 52 which operates the frames 34 which carry the guide pulleys 41 and 42 and shift the same to properly locate the box or load.

I claim:

1. The combination with a traveling crane having hoisting cables at opposite sides thereof, of a shifting frame at each side of the crane, guide pulleys on each frame, from which the cables hang respectively, and means carried by the crane to simultaneously shift the frames in opposite directions and thereby turn the load to an angle with respect to the normal line of travel of the crane, said means comprising a shaft carried by the crane and extending across the same and driving connections between each end of the shaft and one of the frames.

2. The combination with a traveling crane having hoisting cables at opposite sides thereof, of a shifting frame at each side of the crane, guide pulleys on each frame, from which the cables hang respectively, and means carried by the crane to simultaneously shift the frames in opposite directions and thereby turn the load to an angle with respect to the normal line of travel of the crane, said means comprising a shaft extending across the crane, gearing carried by the shaft, and racks carried by the frames and engaging said gearing.

3. The combination with a horizontally traveling crane having a pair of hoisting cables at each side, adapted to engage opposite sides of a load, roller bearings mounted

- on opposite sides of the crane, a pair of horizontally shiftable frames mounted on said bearings at opposite sides of the crane, guide pulleys carried by said frames and from which the cables hang, and power means to shift the frames on their bearings and thereby shift the points of suspension of the cables at the respective sides.
4. In combination, a frame, a trackway carried thereby, a laterally shiftable member on the trackway having a pair of guide sheaves, a cable anchored at one end to the frame and then depending in a bight between the pair of sheaves, a floating pulley in the bight adapted to be connected to the load, means for shifting the shiftable member transversely of the frame, causing the reaches of the cable to pay in and pay out simultaneously, and means for winding in the other end of the cable to raise the load.
5. A hoisting mechanism having a main frame, a shiftable frame mounted thereon and carrying two pairs of sheaves, a hoisting mechanism, a pair of cables leading therefrom in opposite directions across one sheave of each pair respectively and thence depending in a bight and then passing upwardly across the other sheave of the respective pairs and finally anchored to the frame, and a pair of load engaging members having movable pulleys occupying the two bights.
6. A hoisting mechanism of the character described having a main frame, a pair of shiftable frames mounted thereon, mechanism for shifting the latter frames in opposite directions, each latter frame having a pair of sheaves adjacent each other and rotating in the plane of the shift, and hoisting cables leading from the raising mechanism passing downwardly over one sheave, thence in a bight about a movable sheave carrying a load engaging member, thence upwardly over the other sheave and anchored at its end to the main frame.
7. A hoisting mechanism of the character described having a hoist frame, a pair of shiftable frames thereon, mechanism for shifting said frames in opposite direction, each shiftable frame being provided with two pairs of cooperating sheaves, a raising mechanism mounted on the main frame, four
- raising cables passing from the raising mechanism across one member of each pair of said shiftable sheaves, thence downwardly in a bight and upwardly across the other member of said pair and finally anchored to the main frame, four load engaging members having sheaves occupying the respective bights, and mechanism for shifting the two shiftable frames simultaneously in opposite directions.
8. In a hoisting mechanism, the combination with a main frame, of a cable-operating mechanism thereon and cables secured at one end thereto, a pair of shiftable frames on the main frame, guide sheaves mounted on the shiftable frames and having the cables depend over them, the other ends of the cables being anchored to the main frame, an upwardly facing rack on one shiftable frame, a downwardly facing rack on the other shiftable frame, a shaft having pinions engaging the respective racks, and means for rotating said shaft to shift the frames simultaneously in opposite directions.
9. In combination a rigid frame, four cables anchored thereto and each depending in a bight, four sheaves in the bights respectively, load engaging means carried by said sheaves and positioned adjacent the four corners of a rectangle, guide sheaves for locating the bights, and means for moving the guide sheaves in their own plane and relative to the frame and to the points of anchorage of the cables, said last mentioned means permitting the skewing of the load while it is maintained at a substantially constant elevation.
10. A hoisting apparatus having a frame, a winding mechanism mounted thereon, a pair of opposed sheaves shiftable as a unit on the frame and relative to the winding mechanism, a flexible member leading from the winding mechanism and depending in a bight by passing over and between said sheaves, a floating pulley in said bight adapted to be connected to the load, and mechanism for shifting the pair of sheaves as a unit in their own plane.

In testimony whereof, I hereunto affix my signature.

FRANCIS W. BORKES.
